UNITED STATES PATENT OFFICE.

DAVID M. DAVIS, OF MAQUOKETA, IOWA.

TRUSS.

Application filed October 27, 1924. Serial No. 746,117.

To all whom it may concern:

Be it known that I, DAVID M. DAVIS, a citizen of the United States, residing at Maquoketa, in the county of Jackson and State of Iowa, have invented certain new and useful Improvements in Trusses, of which the following is a specification.

This invention relates to improvements in trusses and has as one of its objects to provide a truss which will be exceptionally light in weight and will possess a desirable degree of flexibility and resiliency, thereby rendering it comfortable to wear and permitting of maximum freedom of movement of the limbs and the body muscles without any likelihood of displacement of the truss.

Another object of the invention is to provide a truss so constructed that galling and chafing will not result from its use and, in this connection, the invention contemplates the provision, in a truss, of pads so constructed as to provide for ventilation at the parts of the body engaged by the pads, so that galling and chafing is particularly prevented at these points.

Another object of the invention is to provide a truss so constructed that pads of one type may be removed and pads of another type substituted therefor, as conditions may dictate.

Another important object of the invention is to provide, in a truss, the combination of groin pads and an umbilical or navel pad supported in a novel manner between and above the groin pads, whereby, when conditions require the application of pressure to the umbilicus, the single appliance may be employed instead of resorting to the use of two separate and distinct appliances, one for the groin, and the other for the umbilicus.

In the accompanying drawings:

Figure 1 is a view in front elevation of the truss embodying the invention applied, the outlines of the body being shown in dotted lines.

Figure 2 is a rear elevation of the truss applied.

Figure 3 is a vertical front to rear sectional view taken substantially on the line 3—3 of Figure 2, looking in the direction indicated by the arrows.

Figure 4 is a horizontal sectional view taken substantially on the line 4—4 of Figure 3, looking in the direction indicated by the arrows.

Figure 5 is a horizontal sectional view

taken substantially on the line 5—5 of Figure 1, looking in the direction indicated by the arrows.

Figure 6 is a fragmentary view in elevation illustrating a slight modification of the invention.

The truss embodying the invention comprises a hip belt indicated in general by the numeral 1, the same comprising a strap 2 and a strap 3 of leather or other pliable material suitable for the purpose. The straps 2 and 3 are designed to fit over and encircle the hips, as clearly illustrated in Figures 1 and 2 of the drawings, and the forward end portion of each strap comprises a pair of plies 4 and 5 which are marginally stitched together so as to provide a pocket indicated by the numeral 6, this pocket extending longitudinally of the end portions of the respective straps. The pads of the truss which are to be adjusted to bear against the groin, are supported by a wire frame indicated in general by the numeral 7, and this frame comprises a straight, substantially horizontally disposed intermediate portion 8, at the ends of which bends 9 are formed, and beyond these upwardly directed bends, the wire comprising the frame has its end portions extended upwardly and rearwardly on suitably curved lines, as indicated by the numeral 10, and fitted into the pockets 6 of the respective straps 2 and 3. The extremity of each portion 10 of the frame is flattened as indicated at 11, and formed with an opening indicated by the numeral 12. Small bolts 13 are passed through the plies 4 and 5 of the straps and through the said openings 12. Each carries a securing nut 14 which, when tightened to bear against the ply 5, will serve to securely hold the bolt in place. In this manner, the ends of the wire frame 7 are anchored in the pockets 6 of the straps 2 and 3 and it will be evident that when the straps are fitted about the hips, the wire frame 7 will extend across the abdomen, the portions 10 of the frame being inclined downwardly and forwardly from the strap ends, as clearly shown in Figures 1 and 2. Any suitable means may be provided for adjustably connecting the rear ends of the straps 2 and 3, such for example as a tongue 15 carried by the rear end of the strap 3 and engageable interchangeably in openings 16 formed in the rear end portion of the strap 2.

The groin pads of the truss are indicated in general by the numeral 17 and inasmuch

as these pads are of counterpart construction, a specific description of one will suffice for both. Each of the pads 17 is preferably formed from aluminum or some other light metal and has a substantially elliptical contour, each pad being of hollow concavo-convex form and being designed, of course, to have its convex side presented toward the body of the wearer of the truss. Each pad 17 is formed centrally with an opening 18, and a bolt 19 which is formed with a longitudinally extending diametric slot 20, has its portion at the opposite sides of the slot and at one end, overturned as at 21, in the opening 18, so as to securely anchor the bolt in place, with its threaded shank projecting within the concavity of the pad, a nut 22 being threaded upon the shank of the bolt and tightened to bear against the inner or concave face of the pad in the manner clearly shown in Figure 5 of the drawings. A washer 23 is fitted onto the bolt 19 and rests against the nut 22, and a similar washer 24 is likewise fitted upon the bolt, the respective portion 10 of the frame 7 being fitted through the slot 20 in the bolt and confined between the washers 23 and 24. A nut 25 is threaded onto the outer end of the bolt and is adapted to be tightened so as to cause the washers 23 and 24 to exert clamping action against the said portion 10 of the frame and thereby hold the pads in the desired position of adjustment. At this point it will be evident that by loosening the nut 25, the respective pad 17 may be slidably adjusted along the respective portion 10 of the frame 7 to any desired position and that likewise it may be angularly adjusted about the said portion of the frame so that when the belt is tightened, the pads may be caused to exert pressure in a more or less upward direction at the points where the rupture or hernia is located. It will also be observed that the major ends of the pads 17 are presented laterally outwardly and their minor ends are presented toward each other or laterally inwardly, so that the pads will best conform to the contour of the body and properly exert pressure thereagainst. It will furthermore be evident, by reference to Figure 5, that the overturned head 21 of the bolt 19 is flush with the outer or convex surface of the respective pads 17 so that no inconvenience is caused the wearer of the truss, it being intended, furthermore, that the truss shall be worn over the under garments. To provide for ventilation of the surface of the body at the points of engagement of the pads therewith, each pad is formed with a number of perforations 26 distributed in any preferred manner over its area.

Due to the fact that the outer ends of the members of the frame 7 may be removed from the pockets 6 in the straps 2 and 3 of the belt 1, the pads 17 may be removed, if

occasion requires, and pads of different size or different contour substituted therefor.

The umbilical pad is indicated in general by the numeral 27 and is supported by a frame indicated in general by the numeral 28. The said frame 28 is formed from a suitable length of wire bent to provide spaced side members 29 and a connecting portion 30 extending between the upper ends of the said side members. The side members 29 at their lower ends are bent to provide eyes 31 which are of a diameter to loosely receive the intermediate portion 8 of the frame 7, as clearly shown in Figures 1, 2 and 3 of the drawings, thereby providing for forward or backward tilting of the frame 28 as a whole, under conditions which will presently be described. The pad 27 is, like the pads 17, preferably formed of aluminum and is, generally speaking, of circular form, the same comprising a concavo convex body 32 having a circumscribing outstanding flange 33, the body being formed with a plurality of openings 34 for the purpose of ventilation. The numeral 35 indicates a plate which is disposed to extend transversely of the outer or concave side of the pad 27 and is secured thereto by bolts indicated by the numeral 36, the bolts being secured to the said plate 35 at the ends thereof and through the flange 33. The plate is formed between its ends with an opening 37, and a bolt 38 is fitted at one end through the said opening 37 and is formed with a longitudinally extending diametric slot 39, the said end of the bolt at opposite sides of the slot being overturned in opposite directions as at 40 so as to provide a head engaging a washer 40' which is fitted on the bolt and bears against that face of the plate 35 which is presented toward the concave side of the pad. A washer 41 is also fitted on the bolt and bears against the forward face of the plate 35, as shown in Figure 3, and the intermediate portion 30 of the frame 28 is fitted through the slot 39 and rests against the said washer 41. A washer 42 is fitted onto the bolt 38 and bears against the other side of the connecting portion 30 of the frame 28, and a nut 43 is threaded onto the bolt and is adapted to be tightened so as to cause the washers 41 and 42 to firmly clamp the said connecting portion 30 of the frame 28 and thereby hold the umbilical pad 27 in different positions of adjustment.

The plate 35 has its end portions outwardly of the periphery of the flange 33 of the pad 27, provided with slots 44, and an elastic waist belt 45 is looped and secured at one end through one of the slots, as indicated by the numeral 46, and at its other end is engaged through the other slot and adjustably connected with a buckle 47 upon the said belt, so that the belt may be adjusted about the waist of the wearer of

the truss and caused to maintain the pad 27 in bearing engagement with the umbilicus.

From the foregoing description of the invention, it will be seen that there is provided a truss which may be readily adapted to the body and the component parts of which may be so adjusted as to adapt the groin and umbilical pads to exert proper pressure against the respective portions of the body. It will also be evident that the pads may be angularly adjusted about their supporting members so as to be presented at any desired angle to the body, depending upon the body contour, and that they may be likewise adjusted longitudinally of their supporting members. Also, it will be evident that the truss will not interfere with freedom of movement of the limbs or the body muscles and that no appreciable inconvenience will be experienced by the wearer of the truss. It will also be evident that where the umbilical pad is not required, it may be readily removed by first loosening one end of the supporting member 7 from the respective strap of the hip belt, removing the corresponding pad 17, pressing together the side members 29 of the frame 28 so as to bring the eyes 31 close together, and then working the eyes along the member 7 and over the said end thereof. It will likewise be noted that ventilation is provided for so that there is no likelihood of galling or chafing of the skin.

It will be understood that inasmuch as the supporting frame member 7 extends between the relatively adjacent forward ends of the straps 2 and 3 comprising the hip belt 1, this member, in effect, constitutes a part of the hip belt and it will be observed that the frame 28 constitutes a support extending above the frame 7 for supporting the umbilical pad.

It will be observed by reference to the drawings, that in the preferred embodiment thereof, the member 8 of the wire frame 7 is formed in two parts connected interengaging eyes 8' so that the two sections of the frame may have relative movement, thereby enabling the appliance to adapt itself to movements of the body.

In that form of the invention shown in Figure 6 of the drawings, the member 8 of the supporting frame for the umbilical pad supporting member has its intermediate portion formed integral throughout its length.

Having thus described the invention, what I claim is:

1. In a truss, a hip belt, a supporting member upon the hip belt mounted for swinging movement with relation thereto, an umbilical pad supported by said supporting member, and a waist belt associated with the umbilical pad.

2. In a truss, a hip belt, a groin pad sup-

ported by the hip belt, a supporting member upon the hip belt mounted for free swinging movement with relation thereto, an umbilical pad supported by said member, and a waist belt associated with the umbilical pad. 70

3. In a truss, a hip belt, a groin pad supported by the hip belt, a supporting member upon the hip belt mounted for free swinging movement with relation thereto, an umbilical pad angularly adjustably mounted upon the supporting member, and a waist belt associated with the umbilical pad. 75

4. In a truss, a hip belt including a forward portion adapted to extend transversely across the body of the wearer, a groin pad supported thereon, a supporting member mounted upon the said forward portion of the hip belt for free swinging movement in a front and rear direction, an umbilical pad angularly adjustably mounted upon the said supporting member, and a waist belt associated with the umbilical pad. 80

5. In a truss, a hip belt having a forward frame member adapted to extend transversely across the body of the wearer, groin pads angularly and slidably adjustably mounted upon the said frame member at opposite sides of the intermediate portion thereof, a supporting member swingingly mounted upon the intermediate portion of the said frame member for free movement forwardly and rearwardly, an umbilical pad angularly adjustably mounted upon the supporting member above and between the groin pads, and a waist belt associated with the umbilical pad. 90

6. In a truss, a hip belt, a frame member extending at the front of the belt and separably connected at its ends with the said belt, a groin pad supported by the said member and adjustably mounted thereon, said pad being removable from the member by movement longitudinally thereof upon separation of the member from the belt, and means for releasably securing said pad in a set position upon said frame member. 105

7. In a truss, a hip belt comprising a pair of hip straps, means adjustably connecting the rear ends of the straps, a supporting frame member connecting the forward ends of the straps and having an intermediate portion and end portions extending rearwardly and forwardly therefrom, a supporting member carried by the intermediate portion of said frame, a pad carried by said supporting member, and groin pads mounted upon the said inclined end portions of the frame member and adjustable longitudinally thereof and also angularly thereon. 115

8. In a truss, a hip belt comprising a pair of hip straps, means for adjustably connecting the rear ends of the straps, the straps at their forward ends having pockets therein, a supporting frame member having portions 120

removably secured in said pockets and extending between the forward ends of the straps, and groin pads supported upon the said frame member and adjustable longitudinally therealong and angularly about the same.

9. In a truss, a hip belt comprising a pair of straps, means for adjustably connecting the rear ends of the straps, a supporting frame member extending between the forward ends of the straps, the said frame member including downwardly and forwardly inclined end portions and a transverse intermediate portion, groin pads mounted upon the said end portions of the frame member, a supporting member swingingly mounted upon the intermediate portion of the frame member, an umbilical pad supported by the supporting member, and a waist belt connected with the said umbilical pad.

10. In a truss, a pad supporting rod, a pad comprising a body, a slotted bolt se-

cured to the body and receiving in its slot the said rod, gripping members upon the bolt at opposite sides of the rod, and a nut threaded onto the bolt and adjustable to cause the said members to grip said rod, whereby the pad may be supported in different positions of adjustment upon the rod. 25

11. In a truss, a hip belt comprising a pair of hip straps, means for adjustably connecting the rear ends of the straps, a supporting frame member extending between the forward ends of the straps, groin pads adjustably mounted upon the said frame member, a supporting member swingingly mounted upon the intermediate portion of the frame member between the groin pads, a plate adjustably mounted upon the supporting member to assume various positions of angular adjustment, an umbilical pad supported upon the said plate, and a waist strap associated with the ends of the said plate. 35

In testimony whereof I affix my signature.

DAVID M. DAVIS. [L. s.]
